EX

DESIGN.

E. S. STRAIT.

BADGE.

No. 15,309.

Patented Aug. 19, 1884.

UNITED STATES PATENT OFFICE.

E. SMITH STRAIT, OF TROY, NEW YORK.

DESIGN FOR A BADGE.

SPECIFICATION forming part of Design No. 15,309, dated August 19, 1884.

Application filed June 18, 1884. Term of patent 3½ years.

To all whom it may concern:

Be it known that I, E. SMITH STRAIT, of the city of Troy, county of Rensselaer, State of New York, have invented and produced a new and ornamental Design for Badges, of which the following is a specification.

My design relates to badges; and it consists, as shown in the accompanying illustration, of a shield having an upper field ornamented with parallel bars; a helmet in relief on the shield, said helmet being ornamented with an eagle at the front, shown with its wings spread and pointed upwardly; arrows in the talons of the eagle; a plume on the helmet, with its attached end beneath the eagle; a visor and visor-strap at the front, and a cape at the rear.

The several features of my design are indicated as follows:

20 The letter S designates the shield; H, the

helmet; E, the eagle; P the plume; V, the visor, and C the cape, and these elements are grouped, as shown in the annexed photograph.

Having thus described my design, what I 25 desire to secure by Letters Patent is—

The design for a badge consisting of the shield S, the helmet H, the visor V, the eagle E, in relief on the front of the helmet, and the plume P, with its attached end beneath the 30 eagle, as shown and described.

Signed at Troy, N. Y., this 16th day of June, 1884, and in the presence of the two witnesses whose names were by them hereto written.

E. SMITH STRAIT.

Witnesses:

CHARLES S. BRINTNALL,
STANLEY M. HOLDEN.
